UNITED STATES PATENT OFFICE.

HERMANN RECK, OF LONDON, ENGLAND, AND ANATOLE BORSU, OF BIELEFELD, GERMANY.

CENTRIFUGAL CREAMER.

SPECIFICATION forming part of Letters Patent No. 697,170, dated April 8, 1902.

Application filed August 6, 1901. Serial No. 71,102. (No model.)

To all whom it may concern:

Be it known that we, HERMANN RECK, a subject of the King of Great Britain, residing at 1 Holborn Circus, in the city of London, England, and ANATOLE BORSU, a subject of the King of Belgium, residing at Falkstrasse 4, Bielefeld, in the Empire of Germany, have invented certain Improvements in Centrifugal Creamers, of which the following is a specification.

The invention relates to that class of centrifugal machines adapted for separating two liquids of different densities from their mixture; and it is primarily designed to facilitate the separation of cream from the "whole milk," so called. In the claims hereto appended the precise improvement will be set out in connection with the accompanying drawings, in which—

Figure 1 is a vertical section of the separator. Fig. 2 is an elevation of a corrugated cylinder which incloses a divided liner. Fig. 3 is an elevation of the divided liner, and Fig. 4 is a plan view thereof.

Referring first to Fig. 1, the drum *l*, provided with a cover, is rotated in a suitable casing. *g* is a sleeve to which are attached the ribs *d*. This sleeve is formed of a hollow cylinder which when placed over the central section of the bowl forms a passage for the whole milk, which passes thence through the delivery-tubes *h h* into the bowl. Outlets are provided for the skim-milk through the tubes *m n* and for the cream at *k* through the screws shown, these latter being adjustable to allow of the thickness of the cream-layer being varied. *a a* are the plates, which are shown in this case four in number and tapered vertically, so as to be nearer the central sleeve *g* at the top than at the bottom. They are attached to this sleeve *g* by means of the ribs *d*, and are further connected with each other by pieces *b b b*, so that the one plate is held apart from the other and so that one edge *f* is held nearer to the center of the bowl than the other edge *e*. As to which edge is the nearer to the center depends upon the direction in which the bowl is rotated, being, as shown at *e* and *f*, when the direction is that indicated by the arrow in Fig. 4. On

the outside of the plates *a* wings *c* are provided, which may either adjoin the edge *e*, as shown, or may be attached in any other suitable position on the outer surface of each plate. The bottom edges of the plates are bent so as to form a flange *q*, on which rests the perforated cylindrical covering *i*, and this in conjunction with the wings *c* divide the interior of the bowl into a series of cells, thus preventing the readmixture of the milk and cream particles after once being separated. These plates may be of a larger number than four in larger-sized machines.

The whole milk enters the bowl through the tubes *h*, as shown by the arrows, when it immediately flies against the plates *a* if the bowl is empty and gradually proceeds to fill the bowl. The free surface of the liquid approaching the center is a vertical and approximately a straight line if the drum is revolving at full speed. When the vertical line of liquid approaches as near to the center as the outlets *k* and *n*, cream and skim-milk, respectively, will immediately issue therefrom. When the bowl is revolving under normal conditions, it will be filled to the vertical level of the outlets, when the whole milk enters at *h* and separation will begin almost immediately, the lighter globules of cream going at once to the center and the skim-milk passing outward until it meets the plates *a*, when it is directed either down under the flange *q* or out through the slots between the edges *e f*. In the former case it is the most easily-separated milk which passes to the outside of the cylindrical cover *i* and rising in the space between the cover and the side of the bowl reaches the mouth of the outlet-tubes *m*. The milk passing through the upright slots is not wholly separated and undergoes a further separative action in the space between the plates *a* and the cover, which is divided into cells by the wings *c*. The cream particles here separated pass up the slanting surface of the plates *a* to the top of the cream-column, and the whole milk passes out of these spaces through the perforations in the cover *i*.

The cover is prevented from turning relatively to the plates by a suitable holding device.

vice, such as the slot *o*, in which one of the wings *c* can slide.

Having thus described our invention, we claim—

- 5 1. In a centrifugal separating-machine, the combination of a rotating bowl and a central feed-sleeve provided with a series of arcual plates having radial ribs connecting them at their upper ends with said sleeve, said plates 10 also being inclined upwardly toward said sleeve and forming a divided liner having slots extending from base to top of the liner, and suitably connected together, substantially as set forth.
- 15 2. In a centrifugal separating-machine, the combination of a rotating bowl and a central feed-sleeve having a series of arcual plates provided with radial ribs connecting them to said sleeve and inclined upwardly and toward 20 said sleeve, and forming a divided liner having slots extending from the base to the top of the liner, said plates being connected upon opposite sides of said slots by short pieces, substantially as set forth.
- 25 3. In a centrifugal separating-machine, the combination of a rotating bowl and a central feed-sleeve having a series of arcual plates inclined upwardly and toward said sleeve and having slots therebetween, also having radial 30 ribs connecting the edges of said plates nearest the center of the bowl with the said central sleeve, forming a series of partially-closed cells, around said central sleeve, connected with the space outside of the liner-plates by 35 said slots.
4. In a centrifugal separating-machine, the combination of a rotating bowl and a central feed-sleeve having a series of arcual plates provided with radial ribs connecting them to 40 said sleeve and inclined upwardly and toward said sleeve, said plates forming a divided liner with longitudinal slots between the edges of the plates, and radial wings attached to the exterior edges of said liner- 45 plates, farthest from the center of the bowl.
5. In a centrifugal separating-machine, the combination of a rotating bowl and a central feed-sleeve having a series of horizontally-curved plates connected by radial ribs to said 50 sleeve and inclined upwardly and horizontally toward said sleeve, said plates forming a divided liner with longitudinal slots between the edges of the plates, and radial

wings attached to the exterior surface of said plates.

6. In a centrifugal separating-machine, the combination of a rotating bowl, a central feed-sleeve having a series of horizontally-curved plates connected by radial ribs to said sleeve and inclined upwardly and toward said sleeve, 60 said plates forming a divided liner with longitudinal slots between the edges of the plates, and a perforated cylindrical cover inclosing said liner-plates, open at its upper end and mounted on the lower edges of the plates, and 65 separate outlets for the cream and milk.

7. In a centrifugal separating-machine, the combination of a rotating bowl and a central feed-sleeve having a series of horizontally-curved plates connected by radial ribs to said 70 sleeve and inclined upwardly and toward said sleeve, said plates forming a divided liner, radial wings attached thereto, a perforated cylindrical cover inclosing said liner and forming, with said wings, partially-closed 75 cells, said plates having between them longitudinal slots connecting the cells on the interior with those on the exterior of said liner.

8. In a centrifugal separating-machine, the combination of a rotating bowl, a central feed-sleeve having a series of horizontally-curved plates connected by radial ribs to said sleeve and inclined upwardly and toward said sleeve, 80 said plates forming a divided liner, with longitudinal slots between the edges of the plates, 85 radial wings attached to said plates, a corrugated cylindrical cover inclosing said plates and having perforations in the depressions and ridges of the corrugations, outlets at the top of the bowl for the cream, and pipes having their inlet at the top of the bowl and their outlet at the bottom of the bowl for the outflow of the skimmed milk.

In testimony whereof we have signed our names to this specification in the presence of 95 the subscribing witnesses.
